J. H. HOLLAND,
ATTACHMENT FOR SODA FOUNTAIN FAUCETS.
APPLICATION FILED APR. 23, 1920.

1,347,373.

Patented July 20, 1920.

UNITED STATES PATENT OFFICE.

JAMES H. HOLLAND, OF ST. LOUIS, MISSOURI, ASSIGNOR TO HOLLAND MANUFACTURING CO., OF ST. LOUIS, MISSOURI, A CORPORATION OF MISSOURI.

ATTACHMENT FOR SODA-FOUNTAIN FAUCETS.

1,347,373.

Specification of Letters Patent.

Patented July 20, 1920.

Application filed April 23, 1920. Serial No. 375,981.

To all whom it may concern:

Be it known that I, JAMES H. HOLLAND, a citizen of the United States, residing at the city of St. Louis and State of Missouri, have 5 invented a new and useful Attachment for Soda-Fountain Faucets, of which the following is a specification.

This invention relates to attachments for soda fountain faucets, and consists in the 10 novel construction hereinafter disclosed.

An object of the invention is to provide an attachment for soda fountain faucets having a stirrer element arranged to be rotated by the discharging liquid, whereby the 15 syrup is thoroughly intermixed with the liquid discharged from the faucet.

Another object of the invention is to provide, in connection with a soda fountain faucet, means for agitating the contents of 20 the container in which the liquid is discharged from the faucet incidentally to the delivery of the liquid into the container.

Additional advantages of the construction will be apparent from the following 25 detailed description thereof taken in connection with the accompanying drawing, in which—

Figure 1 is an elevation of a soda fountain faucet including the attachment of the 30 present invention.

Fig. 2 is a vertical section illustrating the details of construction of the improved attachment.

Fig. 3 is a cross section taken substantially 35 on the line 3—3 of Fig. 2.

Fig. 4 is a cross section taken substantially on the line 4—4 of Fig. 2.

Fig. 5 is a cross section taken substantially 40 on the line 5—5 of Fig. 2.

Fig. 6 is a cross section taken substantially 45 on the line 6—6 of Fig. 2.

The attachment of the present invention is designed to be applied to the conventional form of soda fountain faucets that includes 50 the usual supply pipe 1 connected with a source of liquid supply furnished to said pipe under pressure. The pipe 1 enters a valve casing 2 that is controlled by a valve handle 3. The casing 2 has a central discharge passage 4 therein and separate discharge passages 5.

The valve plug that is controlled by the 55 valve handle 3 is arranged to place the supply pipe 1 in communication with the central discharge passage, or with the dis-

charge passages 5, and also to close all of said passages. When the liquid is discharged from the central passage 4 it is under high pressure and is delivered directly into the glass and is used for gassing the contents of 60 the container in dispensing drinks.

When the supply pipe 1 is in communication with the passages 5 the liquid is not discharged directly into the glass, but is baffled against the wall of the spigot and is 65 delivered to the glass without excess pressure, this being the normal adjustment for filling the containers in dispensing drinks. This construction will be recognized as the conventional construction of known soda 70 fountain faucets.

In practice in filling the containers the flavoring fluid is first put in the bottom of the container and the liquid discharged therein through the passages 5. This usual 75 method does not effectively mix the syrup with the liquid and it is necessary to stir the contents of the containers before dispensing the drink. In certain drinks after the container has been approximately filled 80 a limited quantity of the liquid is directly discharged from the passage 4 for gassing the drinks.

The present invention comprises an attachment adapted to be connected with the 85 usual soda fountain faucet and includes a head 6 having an internally threaded recess 7 that screws onto a threaded nipple 8 of the discharge spout of the soda fountain faucet. At the base of the recess 7 the head 90 has a central passage 9 extending therethrough and two passages 10 inclining downwardly and opening into the bottom of the recess 7 at each side of the opening of the passage 9. In the bottom wall of the recess 95 7 and surrounding the opening of the passage 9 is an annular flange 11. Thus, when the head 6 is screwed onto the threaded nipple 8, the passage 9 is in registration with the discharge end of the passage 4, and the 100 passages 10 are in registration with the discharge ends of the passages 5. A tight joint is made at the connection between the head and the nipple 8 and intercommunication between the passages 4 and 5 is prevented 105 by supplying a gasket 12 around the outer wall of the recess and a gasket 13 fitted between the flange 11 and the opening of the passage 9.

A long tube 14 is fitted into the passage 110

9 so that when the valve in the faucet is adjusted to communicate the pipe 1 with the passage 4, there will be a direct discharge of the liquid through the tube 14, 5 so that means is provided for gassing such drinks as are usually prepared by the gassing process. The length of the tube 14 is sufficient so that when the container is brought in position, the discharge end of 10 the tube will be near the bottom of the container.

A second tube 15 is fitted over the tube 14, there being a slight space between the tubes 14 and 15. The upper end of the tube 15 15 is fitted into a recess 16 in the bottom wall of the head 6 and the upper end of the tube 15 has notches 17 therein which register with the discharge ends of the passages 10. Thus, when the pipe 1 is in communication with the passages 5, the liquid will 20 be discharged into the upper end of the tube 15 into the space between the tubes 14 and 15. The tube 15, at a point just below the bottom wall of the head 6, has 25 openings 18 therethrough. The outer wall of the tube 15 is formed so that there is an upper portion 19 thereof and a lower portion 20 thereof of slightly greater diameter than the intermediate section of the tube. 30 The portions 19 and 20 constitute bearings for a tube 21 fitted over the tube 15. The tube 21 contacts with the bearing members 19 and 20 of the tube 15, but does not contact throughout the rest of its length so 35 that it may revolve freely on the tube 15 without excessive friction.

The tube 15 has a threaded portion 22 that extends slightly below the lower end 40 of the tube 21, so that when the tube 21 is slipped over the tube 15 the threaded section 22 will project from the lower end of the tube 21. A nut 23 screwed onto the threaded section 22 serves to hold the tube 21 in adjustment with respect to the tube 45 15. The tube 21 carries at its upper end an enlarged casing 24 that constitutes a chamber into which the liquid discharges from the tube 15 through the openings 18.

In the side wall of the casing 24 are a 50 plurality of inclined discharge passages 25. The passages 25 are arranged at an angle with respect to the axis of the casing 24 so that when the liquid is forced from the chamber in the casing 24, through the passages 25, a rotary motion will be imparted to the tube 21. A spigot 26 is connected with the bottom of the head 6 and surrounds the casing 24 so that after the liquid is forced through the passages 25, it 55 is baffled against the wall of the spigot 26 and is discharged from the lower end thereof into the container placed therebeneath.

Near the lower end of the tube 21 is a stirrer head 27 which will be positioned 60 near the bottom of the container when the

container is in position to receive the liquid from the faucet. Thus, as the tube 21 is rapidly rotated incidentally to the discharge of the liquid into the container, the stirrer head will agitate the heavy flavoring fluid in the container so that after the container has been filled the contents thereof will be thoroughly intermixed and may be served without separately stirring the same.

In order to prevent the fluid under pressure from being forced between the tubes 15 and 21, and discharged directly into the bottom of the container, release passages 28 are provided in the wall of the 80 tube 21 at a point within the spigot 26. Any fluid pressure forced into the space between the tubes 15 and 21 below the casing 24 is thus discharged into the spigot 26 and is prevented from being discharged 85 at the lower end of the tube 21.

From the foregoing it will be understood that the attachment of the present invention may be readily applied to the standard soda fountain faucet and that containers 90 may be filled and gassed in the usual way, and that an effective means is provided for thoroughly agitating the contents incidentally to the filling of the container.

I am aware that the invention may be 95 modified in certain particulars without departing from the spirit and scope thereof. I do not limit myself, therefore, to the exact construction and arrangement shown, but what I claim and desire to secure by 100 Letters Patent, is:—

1. An attachment for soda fountain faucets, having a gassing discharge passage and filling discharge passages, in combination with a revoluble stirrer operated incidentally 105 to the discharge of liquid from said filling discharge passages.

2. The combination with a soda fountain faucet having independent discharge passages, a head adapted to be attached to said 110 faucet having a direct discharge passage and baffled discharge passages therein, a revoluble element, and means for revolving said element by the liquid discharged from said baffled discharge passages.

3. An attachment for soda fountain faucets, comprising a head having a central discharge passage therein and separate discharge passages therein, a tube in connection with said central discharge passage, a tube 120 in communication with said separate discharge passages, a tubular shaft revolubly supported on said second-named tube, a casing in connection with said tubular shaft, and discharge passages in said casing so arranged as to impart rotation to said tubular shaft when liquid is discharged there-through.

4. An attachment for soda fountain faucets, comprising a head having a central dis- 130

- charge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a stirrer head located on one end of said tubular shaft.
5. An attachment for soda fountain faucets, comprising a head having a central discharge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a spigot surrounding said casing.
10. An attachment for soda fountain faucets, comprising a head having a central discharge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a stirrer head located on one end of said tubular shaft.
15. An attachment for soda fountain faucets, comprising a head having a central discharge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a stirrer head located on one end of said tubular shaft.
20. An attachment for soda fountain faucets, comprising a head having a central discharge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a stirrer head located on one end of said tubular shaft.
25. An attachment for soda fountain faucets, comprising a head having a central discharge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a stirrer head located on one end of said tubular shaft.
30. An attachment for soda fountain faucets, comprising a head having a central discharge passage therein and separate discharge passages therein, a tube in connection with said central discharge passage, a tube in communication with said separate discharge passages, a tubular shaft revolubly supported on said second-named tube, a casing in connection with said tubular shaft, discharge passages in said casing so arranged as to impart rotation to said tubular shaft when liquid is discharged therethrough, and a stirrer head located on one end of said tubular shaft.
35. An attachment for soda fountain faucets including a revoluble member, and means for revolving said member incidentally to the discharge of liquid from said faucet, whereby the contents of the container in which said liquid is discharged is agitated as the same is being filled.
40. An attachment for liquid dispensing faucets, including a revoluble stirrer, and means operated incidentally to the discharge of fluid from said faucet for revolving said stirrer.
45. An attachment for soda fountain faucets, comprising a revoluble shaft, a stirrer head on said shaft, and a liquid motor operated by the liquid discharging from said faucet for revolving said shaft.
50. The combination with a soda fountain faucet having a spigot discharge opening, a revoluble shaft extending below the spigot opening, a stirrer head carried by said shaft, and a motor operated by the discharging liquid and being within the spigot whereby 55 said shaft is rotated incidentally to the discharge of liquid into said spigot.
60. The combination with a soda fountain faucet having a spigot discharge opening, a revoluble shaft extending below the spigot opening, a stirrer head carried by said shaft, and a motor operated by the discharging liquid and being within the spigot whereby 60 said shaft is rotated incidentally to the discharge of liquid into said spigot.

JAMES H. HOLLAND.
